METER BOX COVER AND LOCK

Filed June 27, 1922

Patented Mar. 13, 1923.

1,448,202

UNITED STATES PATENT OFFICE.

FRANK E. CROTTO, OF DALLAS, TEXAS, ASSIGNEE TO JOE A. GERRITY, OF DALLAS, TEXAS.

METER-BOX COVER AND LOCK.

Application filed June 27, 1922. Serial No. 571,210.

To all whom it may concern:

Be it known that I, FRANK E. CROTTO, a citizen of the United States, residing at Dallas, in the county of Dallas and State 5 of Texas, have invented certain new and useful Improvements in Meter-Box Covers and Locks, of which the following is a specification.

My invention relates to meter box covers 10 and the object is to provide a simple device for locking the covers to the boxes and which will hold the covers on the boxes for the protection of the meters and to prevent tampering with the meters by un- 15 authorized persons and to provide a locking device which is easily operated and which will not be easily displaced under service conditions. One of the advantages of this improved lock is that it cannot be picked 20 by persons who are disposed to meddle with such devices. Other objects and advantages will be fully explained in the following description and the invention will be more particularly pointed out in the claims.

Reference is had to the accompanying drawing which form a part of this application.

Fig. 1 is a plan view of a meter box and the cover therefor. Fig. 2 is an inverted 30 plan view of the cover with the locking devices applied thereto. Fig. 3 is a broken vertical section, taken on the line 3-3 of Fig. 2. Fig. 4 is an inverted plan view of the plunger lock. Fig. 5 is an inverted side elevation of the same. Fig. 6 is a section of a cover, showing the plunger and the means for locking the plunger in place and the support for the plunger. Fig. 7 is a perspective view of the plunger and support 40 therefor and the key seat. Fig. 8 is a detail view of the spacing rib and of the guide lug, the spring being omitted from the guide lug. Fig. 9 is an inverted view of the stud guide and the co-operating ribs for holding 45 the plunger in different positions. Fig. 10 is a side elevation of the plunger, showing the recesses therein for engaging the locking ribs.

Similar characters of reference are used to 50 indicate the same parts throughout the several views.

The drawings show a meter box 1 and a lid or cover 2 therefor. The edge of the lid 2 is beveled as shown in Figs. 2 and 3. 55 The lid is strengthened by depending ribs 4

and 5 and the lid has a locking lug 6 for engaging the inwardly projecting flange 7 of the meter box. This lug 6 thus locks the lid on one side or point of the periphery. The lid is locked at the diagonally opposite point by a locking plunger 8. The plunger 8 is supported generally by a depending perforated lug 9 which is integral with the lid 2. The plunger 8 is further supported by a stud guide 10 which is integral with a boss 11 which depends from the lid 2. A spring 12 is placed on the stud guide and a cottar pin 13 supports the spring 12. The plunger 8 moves freely in the lug 9, the perforation being large enough to permit angular motion of the plunger so that the plunger can be adjusted on the guide stud 10. The plunger 8 is integral with a body member or slide 14 which has an elongated vertical opening 15 to receive the stud guide 10. 70 The boss 11 has a projection 16, being an integral rib on the lid 2. This spacing rib 16 holds the slide 14 and plunger 8 in parallel relation to the lid 2, that is, this rib 16 prevents upward displacement of the 75 slide and plunger. The plunger 8 and slide 14 are further held in parallel relation to the lid by the spring 12 which holds the plunger and slide yielding upward. The loop member 17 has two locking recesses 18 and 19 in the upper side thereof and the boss 11 has two ribs 20 integral therewith and integral with the stud guide 10. The locking recesses 18 and 19 extend on both 80 sides of the loop 17 but the recess 19 does not extend entirely through the slide 14, just far enough to receive the rib 20. The ribs 20 will occupy either recesses 18 or 19 as may be required. In the locked position the ribs 20 will occupy the recesses 18 and 90 the plunger 8 will engage the flange 7, as shown in Fig. 3. In the unlocked position, the ribs 20 will occupy the recesses 19. A key, shown in dotted outline in Fig. 7, is used to actuate the plunger 8 and slide 14 100 to move the plunger axially or longitudinally. The slide 14 has a key recess or notch 21 to receive the throw arm of the key. A key seat or opening 22 is made in the lid 2 for an operating key of standard 105 type. A boss 23 is formed about the opening 22 to form a bearing for the key. The boss 23 has a depending curved flange 24 for guiding the actuating arm of the key which has a slot for receiving the flange 24. 110

The flange 24 reinforces the key in operation. When the key is turned, the notch in the key arm receives the flange 24 and the key arm is thus guided into the recess 21 5 of the plunger slide for actuating the plunger. When the key actuates or throws the plunger 8 and slide 14, the slide 14 and plunger 8 must yield downwardly slightly until the upper surface of the slide 14 will 10 pass under the ribs 20. The spring 12 will permit the slide 14 and plunger 8 to go down sufficiently for the purpose. The ribs 20 and walls of the recesses 18 and 19 are sufficiently beveled to permit the forcing of the slide 14 15 and plunger 8 axially without making any other provision for depressing the slide and plunger. As the plunger and slide are moving along under the lid, the spring 12 will force the slide and plunger up automatically 20 as soon as one pair of the recesses, 18 or 19, comes under the ribs 20 so that the plunger will stand in the locked or unlocked position.

One of the advantages of this locking device is that the plunger is positioned at 25 one end of the key opening so that instruments for picking the lock cannot reach the plunger for operating the same. Various changes in the sizes, proportions and construction of the several parts may be made 30 without departing from my invention.

What I claim, is,—

1. In a meter box provided with an inwardly projecting flange, a cover for said 35 box having a depending lug for engaging said flange at one point of the circumference of said flange, a key-actuated plunger for engaging said flange at a diagonally opposite point from said lug and provided with 40 locking recesses, means on the underside of said cover including integral ribs adapted to occupy said recesses for normally holding said plunger in position to be actuated by a key, means for holding said plunger in the 45 locked and unlocked position, and means permitting a vertical movement of said plunger to pass from the locked to the unlocked position and vice versa.

2. In a meter box provided with an inwardly projecting flange; a cover for said 50 box having a depending lug for engaging said flange at one point, a key-actuated plunger for engaging said flange at the side opposite from said lug for locking said cover 55 on said box, means on the underside of said cover for normally holding said plunger parallel to said cover in position to be engaged by a key including a perforated lug depending from said cover and a guide stud 60 projecting downwardly through said plunger, and a spring mounted on said stud for holding said plunger yieldingly upward, and means for holding said plunger in a 65 locked position and in an unlocked position as may be required.

3. In a meter box provided with an inwardly projecting flange; a cover for said 70 box having a depending lug for engaging said flange at one point, a key-actuated plunger for engaging said flange at the opposite side from said lug for locking said cover on said box, said plunger having an elongated opening vertically therethrough and having locking recesses in the upper side thereof, locking ribs projecting from said cover for 75 engaging said plunger in said recesses, a guide stud projected from said cover through said elongated opening, and a spring mounted on said stud below said plunger for supporting said plunger and holding the same 80 yieldingly against said locking ribs.

4. In a meter box provided with an inwardly projecting flange; a cover for said 85 box having a depending lug for engaging said flange at one point, a key-actuated plunger for engaging said flange at the opposite side from said lug for locking said cover on said box, said plunger having locking recesses in pairs in the upper side thereof, locking ribs projecting from said cover and adapted to engage one pair of recesses for holding the plunger in the unlocked position and to engage another pair of recesses for holding said plunger in the locked position, said plunger being slidably mounted on the 90 underside of said cover, and means for holding said plunger yieldingly against said locking ribs.

5. In a meter box provided with an inwardly projecting flange; a cover for said 100 box having a depending lug for engaging said flange at one point, a key-actuated plunger slidably mounted on the underside of said cover and adapted to engage said flange 105 at the opposite side from said lug and provided with locking recesses in the upperside thereof, locking ribs projecting from said cover and adapted to enter one pair of said recesses for holding said plunger in the locked position and adapted to enter another pair of said recesses for holding said plunger in the unlocked position, and means for holding said plunger yieldingly against said ribs.

6. In a meter box provided with an inwardly projecting flange; a cover for said 115 box having a locking element for engaging said flange at one point, a key-actuated plunger slidably mounted on the underside of said cover and adapted to engage said flange at the opposite side from said locking element and provided with locking recesses in pairs in the upper side thereof, locking ribs projecting from said cover and adapted to enter one pair of said recesses for holding said plunger in the locked position and adapted to enter another pair of said recesses for holding said plunger in the unlocked position, a guide rib and a perforated lug depending from said cover for holding 120 125 130

said plunger against displacement, and means for holding said plunger yieldingly against said locking ribs and said guide rib.

- 5 7. In a meter box provided with an inwardly projecting flange; a cover for said box having a key opening and a locking element for engaging said flange at one point, a key-actuated plunger slidably mounted on
10 the underside of said cover and adapted to engage said flange at the opposite side from said locking element and disposed beyond the end of said key opening and operating substantially at right angles to said opening, and means depending from said cover
15 for holding said plunger in the locked position and in the unlocked position.

8. In a meter box provided with an inwardly projecting flange; a cover for said box having a depending locking element for 20 engaging said flange at one point and provided with a key opening and a depending guard flange about said key opening, and a locking element slidably mounted on the underside of said cover and disposed at the end 25 of said key opening substantially at right angles thereto and adapted to engage said flange at the opposite side from said first-named locking element and having provision for operation by a key. 30

In testimony whereof, I set my hand this
7th day of June, 1922.

FRANK E. CROTTO.
